United States Patent

Des. 241,553
Patented Sept. 21, 1976

241,553

SPEAKER HORN

Jonas A. Renkus, 2327 Benton Way,
Santa Ana, Calif. 92706

Filed July 14, 1975, Ser. No. 595,542
(Filed under Rule 47(b) and 35 U.S.C. 118)

Term of patent 14 years

Int. Cl. D14—01

U.S. Cl. D26—14 G

FIG. 1 is a perspective view showing the top front and right hand side of a speaker horn showing my new design;

FIG. 2 is an elevation showing the left hand side of the speaker horn of FIG. 1;

FIG. 3 is an elevation showing the rear side of the speaker horn of FIG. 1; and

FIG. 4 is a plan view showing the bottom of the speaker horn of FIG. 1.

I claim:

The ornamental design for a speaker horn, as shown.
